US00D493714S1

(12) **United States Design Patent** (10) Patent No.: **US D493,714 S**
Whitney (45) Date of Patent: **** Aug. 3, 2004**

(54) **VISCOS FLUID DISPENSER WITH
INTEGRAL STORED NOZZLE**

(75) Inventor: **Peter M. Whitney**, Clifton Park, NY
(US)

(73) Assignee: **General Electric Company**, Pittsfield,
MA (US)

(**) Term: **14 Years**

(21) Appl. No.: **29/187,053**

(22) Filed: **Jul. 28, 2003**

(57) **CLAIM**

The ornamental design for viscous fluid dispenser with
integral stored nozzle, as shown and described.

DESCRIPTION

FIG. 1 is a perspective view of a viscous fluid dispenser with
integral stored nozzle showing my new design;

FIG. 2 is rear elevational view thereof; and,

FIG. 3 is a front elevational view thereof.

The portions of the design not shown are disclaimed.

1 Claim, 2 Drawing Sheets

FIG. 1

FIG. 3

FIG. 2
